ROBERT C. ALLEN, OF ESSINGTON, PENNSYLVANIA, ASSIGNOR TO WESTINGHOUSE ELECTRIC & MANUFACTURING COMPANY, A CORPORATION OF PENNSYLVANIA.

MANEUVERING VALVE.

Application filed April 16, 1920. Serial No. 374,451.

To all whom it may concern:

Be it known that I, ROBERT C. ALLEN, a citizen of the United States, and a resident of Essington, in the county of Delaware and State of Pennsylvania, have invented a new and useful Improvement in Maneuvering Valves, of which the following is a specification.

This invention relates to valve mechanism and particularly to that class of valves known as maneuvering valves such as are generally used in controlling turbines used in ship propulsion, and has for its principal object the production of a valve mechanism wherein the main turbine valve, the cruising turbine valve and the reversing turbine valve may be readily operated by means of a single operating mechanism or hand wheel; the production of a valve mechanism wherein a plurality of valves are independently operated by movement of an operating mechanism in opposite directions; the production of a simple, efficient and durable valve operating mechanism; and such other objects as may hereinafter appear. One embodiment of the invention is illustrated in the accompanying drawing wherein—

Fig. 1 is a plan and horizontal sectional view of the valve mechanism showing the valve and levers with the upper portion of the structure removed;

Fig. 2 is a vertical section on the line II—II of Fig. 1 in the direction of the arrows; and

Fig. 3 is a vertical section on the line III—III of Fig. 1 in the direction of the arrows.

Referring to the drawings; the valve mechanism comprises a main valve 1, a cruising valve 2 and a reversing valve 3, each adapted to close port chambers 4, 5 and 6 respectively, through which steam is supplied to a main turbine, a cruising turbine and a reversing turbine, respectively. The valves are all in communication with a valve chest 7, common to all the valves, which is supplied with live steam through a supply passage 8 leading into the valve chest 7.

The valves 1, 2 and 3 are each provided with vertically extending stems 9, 10 and 11, respectively, each carrying on its upper end a socket 12 which supports a helical spring 13, mounted between the socket 12 and a socket swivel 14 carried by an adjusting

screw 15 threaded in the upper portion of a cage 16, which is secured to the valve chest in any suitable manner. The purpose of the spring 13 is to yieldingly hold the valve in closed position as indicated in Figs. 2 and 3. The tension of the spring may be adjusted by the adjusting screw 15.

The main valve 1 and the cruising valve 2 are arranged in one group of valves and between this group and the reversing valve 3 is mounted a horizontal shaft 17, which is carried upon brackets 18 secured to the steam chest casing. A valve operating lever 19 is pivoted to the shaft 17 so that it may oscillate thereabout, and this lever is provided with a loose bearing member 20 through which the stem 11 of the valve 3 passes and which engages the lower extension of the socket 12, so that when the lever 19 is raised, it will cause the valve 3 to be raised against the compression of the spring 13, thereby permitting steam in the chest 7 to pass through the port 6 to the reversing turbine. This bell crank lever 19 carries on a depending short arm 21, a sliding T-shaped selector bar 22, which is adapted to be moved in a direction parallel with the shaft 17 by means of a selector lock 23, adapted to reciprocate in a direction parallel with the shaft 17 upon a guide 24 mounted upon the brackets 18. The selector bar 22 is provided with a depending tooth 25 which extends downwardly into an arcuate groove 26 in the upper surface of the selector lock 23. The selector lock is adapted to be reciprocated by a lever 27 pivoted to the bracket 18 by a pivot pin 27 and this lever may be operated by any suitable rod 28 or by other preferred means. It will be seen that manipulation of the lever 27 will cause the selector bar 22 to be moved so as to protrude from either side of the short arm 21 of the bell crank lever 19.

The main valve 1 and the cruising valve 2 are adapted to be operated by means of bell crank levers 29 and 30, respectively, which are of substantially similar construction. The levers 29 and 30 are provided with depending short arms 29a and 30a, respectively, which arms are adapted to align with the short arm 21 of the bell crank lever 19 when the levers are in neutral position. The long arm of the levers 29 and 30 are each provided with a loose fitting bear-

ing block 31 through which the stems 9 and 10 extend and engage the lower extension of the spring sockets 12 on the valve stems 9 and 10. When the levers 29 and 30 are raised they will cause the valves 1 and 2 respectively to be lifted from their seats and permit steam to flow through the ports 4 and 5 respectively to the main turbine and cruising turbine respectively. The short arms of the levers 29 and 30 are each provided with a T shaped groove similar in contour to the T shaped selector bar 22 so that when the levers 29, 30 and 19 are in neutral position the selector bar 22 may be alternatively moved into the slots on the levers 29 and 30 so as to operatively connect alternately the levers 29 and 30 with the lever 19.

Referring to Fig. 2, it will be seen that if the selector bar 22 is moved into operative connection with either of the levers 29 and 30 that downward movement of the lever will cause upward movement of either lever 29 or 30, to which the lever 19 is at the time connected. This downward movement of the lever 19 will not affect the valve 3. Upward movement of the lever 19 will raise the valve 3, but will not operate either of the valves 1 and 2. It will be seen, therefore, any one of the three valves may be operated independently of the remaining valves by manipulation of the lever 19.

This lever is operated by a link 32 pivoted to the free end of the lever 19 and to a screw block 33 suitably guided for vertical movement by any preferred form of guide means, not shown. A screw 34 mounted in suitable bearings, not shown, passes through the block and is rotated by means of a beveled gear 35 carried by the lower end of the screw and which meshes with a similar bevel gear 36 operated by a rod 37 which carries at its end a hand wheel 38. Rotation of the screw 34 in one direction will cause upward movement of the valve 19 and rotation of the screw in the reverse direction will cause downward movement of the valve lever 19.

The operation of the valve mechanism is as follows: Assuming that the valves 1, 2 and 3 are in the closed position indicated in the figures and that the valve operating mechanism 29 and 30 are in their neutral positions as indicated in Fig. 2, and that it is desired to open the main valve without causing the opening of the cruising or reversing valves, this result may be accomplished by manipulating the lever 27 so that it will move the selector bar 22 into operative connection with the short arm 29a of the lever 29. After this connection has been made, the hand wheel 38 is rotated so as to cause downward movement of the screw block 33 which, in turn, causes downward movement of the lever 19 and consequent upper movement of the lever 29 con-

trolling the main ahead valve 1. If it is desired to cut out the main ahead turbine and use the cruising turbine, the hand wheel 38 is manipulated so as to bring the valve lever 19 into neutral position at which time the main ahead valve will be closed. The selector lever 26 may then be manipulated so as to move the selector bar 22 to the left (see Fig. 3) until it operatively connects the valve lever 19 with the lever 30. The hand wheel 38 is then rotated so as to lower the lever 19 which operation will cause consequent upward movement of the lever 30 which controls the cruising valve 2.

If it is desired to operate the reversing turbine, it will first be necessary to shut the valve which may be open to either the main ahead turbine or the cruising turbine, before the reversing valve is opened. To open the reversing valve the hand wheel 38 is reversed until the lever 19 has permitted the open main ahead valve or cruising valve, as the case may be, to close, and until the lever 19 is raised above neutral position, which action will cause the opening of the valve 3. It will be seen with this construction that it will be impossible to open the reversing valve 3 without first causing the main ahead valve or the cruising valve to be closed, and vice versa, so therefore a perfectly safe arrangement is provided for the functioning of the valves.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. A valve mechanism comprising in combination three separately operative valves, means for actuating one of the valves, and a selecting means for alternatively operatively connecting either one of the remaining valves with the said valve actuating means.

2. A maneuvering valve comprising in combination a main ahead valve, a cruising valve, a reversing valve, means for actuating one of the valves, and a selecting means for alternatively connecting either one of the remaining valves with the said valve actuating means.

3. A maneuvering valve, comprising in combination a main ahead valve, a cruising valve, a reversing valve, means for actuating the latter valve, and a selecting means for alternatively connecting either one of the remaining valves with the said valve actuating means.

4. A valve mechanism comprising in com-

bination, three valves, means for actuating the valves whereby movement of the means in one direction actuates one valve and movement of the actuating means in the 5 reverse direction actuates either of the remaining valves, and a selecting means for alternatively operatively connecting the remaining valves with the said valve actuating means, whereby either of the remaining 10 valves may be operated independently of the first valve.

5. A valve mechanism, comprising in com-

15 combination three independently operative valves, adapted to be seated by movement in the same direction, a valve operating member for the valves so disposed with respect thereto that movement of the operating member in one direction opens one of the valves, and selecting mechanism for alternatively operatively connecting the remaining valves so that either of the remaining valves may be opened when the operating member is moved in the reverse direction.

25 6. A valve mechanism, comprising a plurality of valves arranged in two groups, a shaft between the groups, a valve operating lever pivoted to the shaft, adapted to operate the valve or valves in one group, operating levers pivoted to the shaft for separately operating the valves in the other group, and a selecting means for alternatively connecting the operating levers with the said valve operating lever whereby any 30 valve of the second group may be actuated independently of any other valve in the same group by movement of the said 35 valve operating lever.

7. A valve mechanism, comprising in combination a plurality of valves, an operating lever for each valve provided with interlocking means adapted to operatively align when the valves are in neutral position, and a selector carried by one of the levers adapted to cooperate with the interlocking means whereby any of the other levers may be alternatively interlocked in operative relation therewith.

8. A valve mechanism comprising in com-

bination a plurality of valves, a lever for 50
operating one of the valves when moved in
one direction, a selector carried by the lever,
and operating means for the remaining
valves adapted to be operatively engaged
by the selector whereby the remaining valves
may be operated alternatively by the valve
lever when the said lever is operated in the
reverse direction. 55

9. A valve mechanism comprising in combination a plurality of valves, a lever for operating one of the valves when moved in one direction, a selector carried by the lever, and operating means for the remaining valves adapted to be operatively engaged by the selector whereby the remaining valves may be operated alternatively by the valve lever when the said lever is operated in the reverse direction. 60 65

10. A valve mechanism comprising in combination a plurality of valves, a lever for operating one of the valves when moved in one direction, a selector slidably carried by the valve lever, an operating lever for each of the remaining valves, adapted to be alternatively operatively engaged by the selector, whereby the levers may be alternatively operated to actuate the remaining valves when the valve lever is moved in the reverse direction. 75

11. A valve mechanism comprising a plurality of valves, means for normally biasing the valves to closed position, levers for opening the valves having one-way transmitting connections with respect thereto, means whereby one lever may be selectively connected to either of the other levers, and means for moving the latter lever in both directions, movement in one direction resulting in the opening of the associated valve and movement in the other direction resulting in the opening of the valve associated with the lever selectively coupled thereto. 80 85 90

In testimony whereof, I have hereunto
subscribed my name this 30th day of March, 95
1920.

ROBERT C. ALLEN.
